Des. 217,080
Patented Mar. 31, 1970

217,080

LETTER FILE

Jack Fairchild Fleming, Boonton, N.J., assignor to Sterling Plastics Co., Mountainside, N.J., a corporation of New Jersey

Filed Apr. 11, 1969, Ser. No. 16,690

Term of patent 14 years

Int. Cl. D3—01

U.S. Cl. D87—5

FIG. 1

FIG. 2

FIG. 3

FIG. 4

FIG. 1 is a perspective view looking toward the top, one end and the front side of a letter file embodying my new design;

FIG. 2 is a perspective view looking toward the top, the other end and the back side thereof, with the carrying handle shown in raised position;

FIG. 3 is a view similar to FIG. 1 but with the lid shown partly open and the handle in raised position; and

FIG. 4 is a bottom plan view thereof.

I claim:

The ornamental design for a letter file, substantially as shown.
